UNITED STATES PATENT OFFICE

MARTIN N. PHILLIPS, OF ELIZABETHTOWN, KENTUCKY, ASSIGNOR OF ONE-THIRD TO
SYDNEY J. BUSH, OF LEXINGTON, KENTUCKY.

RAIL-JOINT.

1,188,557.

Specification of Letters Patent. Patented June 27, 1916.

Application filed December 8, 1915. Serial No. 65,758.

To all whom it may concern:

Be it known that I, MARTIN N. PHILLIPS, a citizen of the United States, residing at Elizabethtown, in the county of Hardin and 5 State of Kentucky, have invented certain new and useful Improvements in Rail-Joints, of which the following is a specification.

My invention relates to improvements in 10 rail joints.

An important object of the invention is to provide means of the above mentioned character, adapted to form a smooth and continuous joint between the adjacent ends 15 of the rails, and which is exceedingly strong and durable.

A further object of the invention is to provide a rail joint of the above mentioned character, so constructed that the parts 20 thereof will not work loose, and the weight of the load carried by the rails will be taken off of the bolts whereby they will not become broken.

A further object of the invention is to 25 provide a rail joint of the above mentioned character, which is simple in construction, inexpensive to manufacture, and durable.

Other objects and advantages of the invention will be apparent during the course 30 of the following description.

In the accompanying drawings forming a part of this specification and in which like numerals are employed to designate like parts throughout the same, Figure 1 is a 35 perspective view of a rail joint embodying the invention, Fig. 2 is a plan view of the same, Fig. 3 is a horizontal sectional view taken on line 3—3 of Fig. 6, Fig. 4 is a similar view taken on line 4—4 of Fig. 6, Fig. 5 is a vertical transverse sectional view 40 taken on line 5—5 of Fig. 2, Fig. 6 is a similar view taken on line 6—6 of Fig. 2, Fig. 7 is a perspective view of a base plate and associated elements, Fig. 8 is a bottom 45 plan view of a fish plate, and, Fig. 9 is a perspective view of a short connecting rail.

In the drawings, wherein for the purpose of illustration is shown a preferred embodiment of my invention, the numeral 10 50 designates cross ties, upon which are mounted rails 11. These rails have their vertical webs provided with openings 11'. The inner or adjacent ends of the rails 11 are preferably diagonally cut or beveled, as shown at 12, and a short connecting rail 13

is arranged between these ends, and has its ends diagonally cut or beveled, as shown at 13', to have fitting engagement therewith. This short connecting rail has its base laterally reduced or cut away, as more clearly 80 shown in Figs. 4 and 9, and the vertical web of this connecting rail is provided at a point equidistantly spaced from its ends, with an opening 15, as shown.

The numeral 16 designates a base plate, 85 adapted to receive thereon the bases of the rails 11 and the base of the connecting rail 13. This base plate is provided upon its opposite longitudinal edges with spaced apertured ears or extensions 17 and 18, for receiving spikes 19, which serve to bind the base plate to the cross ties.

Rigidly connected and preferably formed integral with one longitudinal edge of the base plate 16 is a substantially vertical fish 75 plate 20, having an angularly arranged lower portion 21, forming with the base plate 16, a recess 22, for receiving the bases of the rails 11 and 13. As more clearly shown in Figs. 5 and 6, the fish plate 20 is 80 provided at its upper edge with a bead 23, to engage beneath the heads of the rails. The fish plate is also provided beneath this bead 23 with a longitudinal recess 24.

The numerals 25 and 36 designate open- 85 ings or bolt holes formed in the fish plate.

Arranged within the recess 22 is a bar, lug or member 27, preferably cast integral with the fish plate 20 and the base plate 16. The ends of the bar 27 are diagonally cut or 90 beveled, as shown at 28, corresponding to the diagonal cut or bevel of the ends of the rails 11, to have fitting engagement with the bases of these rails.

The numeral 29 designates a co-acting 95 fish plate, having a lower inclined portion 30, carrying spaced apertured ears or extensions 31, which are adapted to be arranged adjacent the ears 18 and to receive the spikes 19. The vertical web of the fish plate 29 is provided at its upper longitudinal edge with a head or bead 32, and beneath this head with a longitudinal recess 33. This fish plate is provided with open- 100 ings or bolt holes 34 and 35, as shown.

Preferably formed integral with the lower side of the inclined portion 30 of the fish plate 29 is a bar, lug or member 36, having its bottom wall 37 flat and adapted to be arranged horizontally upon the base plate 110

2
16. The ends of the bar 36 are diagonally cut or beveled, as shown at 38, corresponding to the diagonally cut or beveled ends of the rails 11, to have fitting engagement therewith.

The numeral 39 designates bolts, which are passed through the openings or bolt holes in the fish plates and the vertical webs of the rails, as shown.

10 As clearly shown in Fig. 3, a pair of bolts is arranged at each end of the connecting rail 13 and a single bolt passes through the center of this connecting rail, making five bolts in all, required for binding the parts 15 of the joints together, in the most highly satisfactory manner.

When the parts of the rail joint are assembled for use, the short connecting rail 13 has its base 14 engaging the base plate 16, and this base 14 is arranged between the bars 27 and 36, as more clearly illustrated in Fig. 4. The diagonally cut or beveled ends 18 of the base 14 coincide with the beveled ends 28 and 38, the same having fitting engagement with the beveled ends 12 of the rails 11. The bolts 39 serve to bind the fish plates to the rails and the spikes 19 anchor the base plate and fish plate to the cross ties.

30 Attention is called to the fact that the rail joint cannot have vertical motion. The expansion is equal on both ends of the short rail, and by using the short rail I dispense with the hinge joint.

35 It is to be understood that the form of my invention herewith shown and described is to be taken as a preferred example of the same, and that various changes in the shape, size, and arrangement of parts may be resorted to without departing from the spirit 40 of the invention or the scope of the subjoined claims.

Having thus described the invention, I claim:

45 1. The combination with rails having their adjacent ends beveled, of a short connecting rail having its ends beveled and arranged between the adjacent ends of the first named rails and having its base laterally reduced, a base plate receiving thereon the base of all of the rails, fish plates arranged upon opposite sides of the short connecting rail and extending outwardly beyond its ends to overlap the ends of the first named 50 rails and having lower angularly arranged portions to engage with the bases of the rails, and bars arranged beneath and rigidly secured to the angularly arranged portions of the fish plates and having their ends 55 beveled to coincide with the beveled ends 60

of the laterally reduced base of the short connecting rail and coöperating therewith to have fitting engagement with the beveled ends of the bases of the first named rails.

2. The combination with rails having 65 their adjacent ends beveled, of a short connecting rail having its ends beveled and arranged between the adjacent ends of the first named rails and having its base laterally reduced, a base plate receiving thereon 70 the bases of all of the rails, fish plates arranged upon opposite sides of the short connecting rail and extending outwardly beyond its ends to overlap the ends of the first named rails and having lower angularly arranged 75 portions to engage with the bases of the rails, bars arranged beneath and formed integral with the angularly arranged portions of the fish plates and extending longitudinally thereof and having their ends beveled to coincide with the beveled ends of the laterally reduced base of the short connecting rail, and coöperating therewith to have fitting engagement with the beveled 80 ends of the bases of the first named rails, bolts passing through the fish plates and rails to bind them together, and means to secure the fish plates to cross ties.

3. The combination with rails having 85 their adjacent ends beveled, of a short connecting rail having its ends beveled and arranged between the adjacent ends of the first named rails and having its base laterally reduced, a base plate receiving thereon 90 the bases of all of the rails, a fish plate formed integral with one longitudinal edge of the base plate and embodying an angularly arranged portion to engage with the bases of the rails and forming a chamber with the base plate, a longitudinally extending 95 bar arranged within said chamber and formed integral with the fish plate and base plate and having its ends beveled, a co-acting fish plate arranged upon the opposite side of the rails and embodying an angularly arranged portion, a co-acting longitudinal bar formed integral with the lower surface of the angularly arranged portion of the second named fish plate and having its ends beveled, bolts serving to bind the 100 fish plates and rails together, and means for securing the base plate and fish plates to cross ties.

In testimony whereof I affix my signature in presence of two witnesses.

MARTIN N. PHILLIPS.
